UNITED STATES PATENT OFFICE.

WENTWORTH MOSBY, OF NEW YORK, N. Y.

DESIGN FOR A CALENDAR-BASE.

SPECIFICATION forming part of Design No. 31,813, dated November 7, 1899.

Application filed September 27, 1899. Serial No. 731,867. Term of patent 3½ years.

To all whom it may concern:

Be it known that I, WENTWORTH MOSBY, a citizen of the United States, residing in the city, county, and State of New York, have invented a new and original Design for a Calendar-Base; and I do hereby declare that the following is a full, clear, and exact description of the same.

Reference is to be had to the accompanying drawing, forming a part of this specification, which is a face view of a calendar-base, showing my new design.

As shown in the drawing, the leading or material feature of my design consists of a rectangular base having a superimposed card on its lower section and a face peering through an opening in a sheet on the upper section of the calendar-base and surrounded by the torn edges of the sheet around said opening. The

face is a humorous face and, together with the sheet *a*, which is of oval form, is of a contrasted color or appearance to the calendar-base *b*. The face and sheet are located at the upper corner of the base, and the figures and words making up the calendar proper are located at the lower portion of the base.

Having thus described my invention, what I claim as new, and desire to secure by Letters Patent, is—

The design for a calendar-base, substantially as herein shown and described.

In testimony whereof I have hereunto set my hand the 21st day of September, 1899.

WENTWORTH MOSBY.

In presence of—

CLARENCE L. BURGER,
LOUIS B. ADAMS.
